(57) **CLAIM**

We claim the ornamental design for a mobile phone, as shown and described.

DESCRIPTION

FIG. 1 is a front perspective view of a mobile phone showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear perspective view thereof.

The dot-dash broken lines and the evenly-spaced broken lines within the solid line showing represent a boundary that forms no part of the claimed design.

The surface adjoining the outer perimeter solid line shown as an unshaded surface in the figures forms no part of the claimed design.

The remaining evenly-spaced broken lines in the figures depict portions of the mobile phone which form no part of the claimed design.
